(57) **CLAIM**

I claim the ornamental design for accessories for inflation and repair of tires, as shown and described.

DESCRIPTION

FIG. 1 is a top/side perspective view of our new design for accessories for inflation and repair of tires;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.
The broken lines are for illustrative purposes only and form no part of the claimed design.
